UNITED STATES PATENT OFFICE

2,262,516

ELECTRIC CIRCUIT BREAKER

David C. Prince, Schenectady, N. Y., assignor to
General Electric Company, a corporation of New
York

Application December 19, 1940, Serial No. 370,819

6 Claims. (Cl. 200—148)

My invention relates to electric circuit breakers, more particularly to circuit breakers of the gas blast type wherein a blast of gas under pressure is directed through the arc formed upon separation of the breaker contacts, and has for its principal object the provision of an improved gas blast circuit breaker for high voltage circuits that is effective in applying the blast for arc interruption and that is efficient in the use of compressed gas.

My invention will be more fully set forth in the following description referring to the accompanying drawing, and the features of novelty which characterize my invention will be pointed out with particularity in the claims annexed to and forming a part of this specification.

Referring to the drawing, Fig. 1 is a plan view of a double-break circuit breaker embodying the present invention, Fig. 2 is an enlarged view partly in section of circuit breaker structure shown in Fig. 1, Fig. 3 is a sectional view of a modified form of my invention and Fig. 4 is a similar view of another form of circuit breaker embodying the present invention.

The double-break circuit breaker shown by way of example in Fig. 1 comprises a movable switch blade or bridging member 1 for completing the circuit between the terminals of the breaker indicated at 2 and 3. The bridging member 1 is preferably rotatably mounted on an insulator 4 so that after arc interruption the terminals 2 and 3 can be suitably isolated with respect to the bridge 1 by air gaps. The fixed terminals 2 and 3 are connected to arc extinguishing chamber housings 5 and 6 respectively, each chamber being connected through a conduit 7 to a suitable source of compressed gas (not shown).

When it is desired to interrupt the circuit, compressed gas is admitted to the conduits 7 to cause separation of the breaker contact structure. A shield 5' is mounted at the end of the chamber housing 5 and is provided with a central aperture through which a contact 8 engages the coacting shield contact 9 on the bridging member. Similarly, the chamber housing 6 is provided with a shield 6' through which the contact 10 operates to engage the corresponding bridge contact 11. When the arcing caused by separation of the aforesaid pairs of contacts has been interrupted by gas blast, the bridging member 1 is rotated by suitable means (not shown) to the isolating position.

Fig. 2 illustrates the arcing chamber at 6 55

with the contacts in closed circuit position. The arcing chamber is formed by an insulating cylinder 12 constituting a guide for the movable rod contact 10. The chamber passage 13 formed within the cylinder is restricted at the exhaust opening 14 so that the contact 10 has a slight clearance. The shield 6' is suitably mounted on the end of the cylinder as illustrated.

The operating means for the contact 10 in the present instance comprises a combined piston and valve structure 15. A piston member 16 is reciprocally operable in an enlarged portion 17 of the cylinder arranged to be in direct communication with the gas supply conduit 1. The piston 16 has secured thereto a cylindrical portion 18 that is guided in the passage 13 so as normally to function as a valve and close that passage with respect to the supply conduit 1. The combined piston and valve structure, which is here shown as directly connected to the movable rod contact 10, is spring biased at 19 toward the circuit closing position. The circuit through the breaker structure above described comprises the contacts 11 and 10, the piston-valve 15, spring 19 and terminal 3.

The operation of the circuit breaker is as follows. When the circuit is to be interrupted by reason of a short circuit or overload, gas under pressure is admitted to the supply conduit 1. Immediately upon admission of the pressure gas to the space 11, the piston 16 is forced toward the right against the bias of spring 19. The initial movement of the contact 10, it will be observed, causes separation of the contacts 11 and 10 resulting in the formation of a short power arc. However, the interrupting gas blast is delayed at this time by reason of the cylindrical valve member 18 which closes the passage 13.

I have found that this initial delay in the application of the blast may under certain conditions result in less deterioration of the switch contact structure by reason of the limited energy, i. e. heat, generated by a short arc. That is, other things being equal, the energy or heat dissipated by an arc is proportional to the length of the arc. If now, the gas blast is prematurely directed through the arc path, the arc itself may be looped so as appreciably to increase the length thereof. In addition, an arc subject to an air blast has higher losses so that it develops more heat than an arc of the same length in comparatively still air. These factors combine to cause excessive generation of heat

with resultant deterioration of the breaker structure.

By premature application of the gas blast is meant subjection of the arc to the gas blast before the arc has reached a predetermined or preferred length for most positive interrupting action. In other words, there is an optimum for the arc length in respect to most effective application of the gas blast. This optimum depends on the nature of the circuit to be interrupted and is the minimum distance that will prevent restriking of the recovery voltage after arc interruption at a current zero.

In the present case, the blast is applied to the arc shortly after the arc has been drawn through the restricted passage at 14. The instant application of a strong high velocity gas blast at this point is effective to cause arc interruption within the restricted passage with minimum generation of heat. It will also be observed that the consumption of compressed gas is no more than that essentially required, since a wasteful and useless premature blast is eliminated.

After interruption of the arc and prior to return of the contact 10 to closed position, the bridging member 1 of the breaker is rotated by suitable means to isolating position. The interrupting chamber at 5 functions in a manner similar to that above described. It will be observed that erosion of the arc chamber at the restricted passage 14 does not affect normal opening of the contacts as in the case of a prior type circuit breaker wherein the build-up of pressure for operating the contacts may be hindered by leakage around the contact at the exhaust opening.

In the modification shown by Fig. 3, the arc is acted upon by a plurality of cross blast jets, instead of by a longitudinal blast. A plurality of strong cross blasts is very effective in interrupting high voltage circuits. The insulating switch casing 20 for the arc chamber is closed at one end by the fixed contact 21 and is provided with lateral blast passages 22 disposed along the arc path. The piston-valve structure 15 is similar to that shown in Fig. 2 and further description thereof is unnecessary. When the breaker is opened the arc is first formed in the passage 13 opposite the cross blast passages. The application of the blast is delayed by the cylindrical valve 18 so that a predetermined length of arc is opposite the cross blast jets before the gas under pressure is admitted to the passage 13. As in the previous case, the short arc is quickly interrupted without excessive generation of heat.

In Fig. 4, the cross blast arrangement is further modified so that the delayed blast is more effective. The insulating casing 30 for the arc chamber is in this case provided with insulating baffles 31 extending across the path of the arc so as to provide transverse blast passages 32. These transverse passages or ports are uncovered as the contacts separate. The cross blast passages 32 are also connected directly to a passage 33 that is opened to the blast pressure only after predetermined separation of the contacts 21—10. This predetermined movement is necessary to uncover the cross blast ports and corresponds to the preferred length of arc, or optimum, above referred to.

The piston-valve structure 15 is in the present case modified to include a recessed portion at 34 arranged to connect the space at 17 with the passage 33 after predetermined movement of the piston 16. The valve portion 34 prevents escape of gas along the longitudinal axis of the arc

so that the blast is entirely directed in the most effective manner through the transverse blast passages 32.

It will be noted that where high pressure storage vessels are used as the source of gas supply, special reducing valves or the like for applying the pressure to the operating means for opening the breaker contacts is unnecessary. Furthermore, no gas is consumed in operating the breaker contacts since all venting takes place across the arc path.

In the case of Figs. 3 and 4, it shall be understood that suitable disconnecting or isolating means can be provided for isolating the circuit breaker after interruption of the arc.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. An electric circuit breaker of the gas blast type comprising relatively movable contacts separable to form an arc gap, means for directing a gas under pressure through said gap for interrupting arcing, and means for blocking flow of said gas through said arc gap after separation of said contacts until said gap has reached a predetermined length, said means thereupon admitting an arc interrupting blast to said gap.

2. An electric circuit breaker of the gas blast type comprising relatively movable contacts separable to form an arc gap, means for directing a gas under pressure through said gap for interrupting arcing, and piston structure operatively related to said contacts to cause separation thereof, said piston structure controlling flow of said gas so that the interrupting blast is positively blocked and delayed until the contacts have separated a predetermined preferred distance for most effective arc interruption.

3. An electric circuit breaker of the gas blast type comprising a pair of contacts, one of which is movable to form an arc gap, means for directing a gas blast through said gap for interrupting arcing, and a piston operatively connected to said movable contact arranged to be acted upon by said gas for causing separation of said contacts, said piston also positively controlling gas passages leading to said arc gap so as to block and delay application of the gas blast until the arc gap has reached a predetermined preferred length for most effective arc interruption.

4. An electric circuit breaker of the gas blast type comprising a fixed contact, and a movable contact separable to form an arc gap, passage means for directing a gas blast from a pressure supply source through said gap for interrupting arcing, and piston structure arranged to control said passage means leading to said arc gap so as to block and delay application of the gas blast until the arc gap has reached a predetermined preferred length for most effective arc interruption.

5. An electric circuit breaker of the gas blast type comprising insulating structure defining an arc chamber, a pair of contacts, one of which is movable to form an arc gap in said chamber, means for directing a gas blast into said chamber and through said gap for interrupting arcing, and combined valve and piston structure operatively connected to said movable contact arranged to be acted upon by said gas for causing

separation of said contacts and also controlling gas passages leading to said chamber so as to block and delay application of the gas blast to said chamber until the arc gap has reached a predetermined preferred length for most effective arc interruption.

6. An electric circuit breaker of the gas blast type comprising insulating structure defining an arc chamber, said chamber having a plurality of laterally disposed exhaust ports, a pair of contacts, one of which is movable to form an arc gap in said chamber across said exhaust ports, means including a passage leading from

a pressure supply source for directing a gas blast into said chamber and through said gap and exhaust ports for interrupting arcing by cross-blast action, and valve structure operatively connected to said movable contact, circuit opening movement incident to separation of said contacts also operating said valve structure to control said passage so as to block and delay application of the gas blast to said chamber until the arc gap has reached a predetermined preferred length for most effective arc interruption.

DAVID C. PRINCE.
